TELEVISION RECEIVER ESCUTCHEON

Richard K. Althans, Mardon Woods, R.R. 2, Long Grove,
Ill. 60047, and Bernard B. Bluestein, 8816A Dee
Road, Des Plaines, Ill. 60016

Filed May 27, 1969, Ser. No. 17,377

Term of patent 14 years

Int. Cl. D14—03

U.S. Cl. D56—4

The single figure is a perspective view of a television receiver escutcheon, showing our new design.

We claim:

The ornamental design for a television receiver escutcheon, substantially as shown.
